UNITED STATES PATENT OFFICE.

PHILIP E. EDELMAN, OF NEW YORK, N. Y.

VARIABLE CONDENSER.

Application filed June 5, 1922. Serial No. 566,130.

To all whom it may concern:

Be it known that I, PHILIP E. EDELMAN, a citizen of the United States, of No. 9 Church Street, city of New York, county of New York, and State of New York, have invented certain new and useful improvements in variable condensers, and more particularly variable air condensers of the Korda type, such as are used in radio apparatus, 10 of which the following is a specification.

My present invention relates to the improvements in the construction and assembly of variable condensers of the class described; and the objects of my improvements are, 15 first, to provide an inexpensive rigid assembly; second, to provide a counterbalance which may be assembled with the movable plates of said condenser; third, to provide an accurate lock for the movable plates 20 without the use of cast-in or soldered construction; fourth, to provide means to lock the plates in true parallel position with respect to each other without the necessity of hand-fitting; fifth, to provide means where- 25 by one or more plates may be easily removed to change the capacity of the device.

I attain these objects by the mechanism illustrated in the accompanying drawings, in which—

30 Fig. 1 is a front elevation showing the assembled condenser; Fig. 2 is a front sectionalized view showing the metal inserts and construction used. Fig. 3 is a plan view projected from the view in Fig. 1. Fig. 4 is 35 a partial section taken along the line AA of Fig. 2; Fig. 5 is a fragmentary view taken along the line BB of Fig. 2. Fig. 6 is a plan and front elevation illustration showing the construction of the movable plates used. Fig. 7 is an illustration showing plan view and front elevation of the blank stamping used for the fixed plates. Fig. 8 is a front elevation and bottom view 40 illustration showing the support post used in Fig. 1. Fig. 9 is a front elevation showing the shaft used for carrying the movable plates. Fig. 10 is a side view projected from Fig. 9; Fig. 11 is a bottom view projected from Fig. 9; Fig. 12 is an illustration showing in front elevation and bottom view 45 the auxiliary support post 27 of Fig. 1 and Fig. 2. Fig. 13 is a plan and a side view illustration showing the construction of the support spring 31; Fig. 14 is an illustration in 50 plan view and in front elevation of the metal part 36 used as a binding post mem-

ber in Fig. 1 and Fig. 2. Fig. 15 is an illustration in plan view and side elevation showing the lock-ring member used on the shaft 17 of Figs. 9 and 2. Fig. 16 is an 55 illustration in plan view and in side elevation sectioned showing the top insulating support member of Fig. 2. Fig. 17 is an illustration and plan view and side elevation sectioned showing the bottom insulating 60 ring used in Fig. 2. Fig. 18 is an isometric view of the lock-bar used in co-operation with the lock-ring of Fig. 15. The lock holds hole 6 of plate 1 shown in Fig. 6, and the slot 26 of member 17 shown in Fig. 18, 70 when assembled as shown in Fig. 1 and Fig. 2.

Similar numerals refer to similar parts through the several views.

Heretofore in construction of variable air 75 condensers of the Korda type which have been known in the art for about 20 years, it has been difficult to obtain an accurate condenser of inexpensive construction, and to maintain the movable plates in accurate 80 alignment with respect to the fixed plates so that a condenser of this type may be shipped through the mails without damage. One of the objects of this invention has in view a simplified new construction which affords a 85 very durable and simple device. Referring now to the individual parts used in the construction, i. e., to say Figs. 6 to 18 inclusive, I will first describe and point out certain features therein, after which I will 90 specify and describe the manner of assembly as shown in Figs. 1 to 5 inclusive.

In Fig. 6, plate 1 is constructed from No. 22, 24 or 26 gauge, and metal such as aluminum, zinc or brass, and may be stamped out 95 in the form shown with a smooth edge 2, a substantially square slot 3, projecting support members 4 and 5 respectively, and a lock hole 6, the purpose of which will presently appear. The fixed plate 7 is similarly 100 stamped out with a smooth edge 8, a rounded portion 14, flattened portions 9 and 10 provided respectively with abutments 12 and 11 and a flattened portion 13, the purpose of 105 which will presently appear.

In Fig. 8, the support post 15, preferably of brass, is provided with interior threaded ends 17 and 18 respectively, and carries a series of slots 16 moulded into its side. These slots are properly proportioned so that 110 the plate 7 when force-fitted into one of the slots 16, is securely held thereby. In Fig. 9,

shaft 17, preferably made from brass in an automatic screw machine, is provided with a threaded portion 18 at the top and a thread 20 at the bottom portion. The portion 25 of this shaft 17 contains a series of slots 24 of proper size such that the plate 1 of Fig. 6 may be inserted into one of said slots 24 snugly. A slot 26 is also moulded into portion 25 of member 17 whereby the lock bar shown in Fig. 19 may be slid into said slot 26 and through said lock hole 6 of member 1 shown in Fig. 6 for the purpose which will be presently described. By referring now to the bottom view projected from Fig. 9, 15 that is to say Fig. 11, it will be seen that the portion 26 is flattened on three sides; that is to say, 25^a, 21 and 23, to fit the slot 3 of member 1 shown in Figure 6 so that member 1 will not be rotatable about shaft member 20. In Fig. 12, the auxiliary brass post 27, carries internal threads 28 at one end and 29 at the other, and is used as shown in Fig. 2 as a support member between the top and bottom insulating disk members shown 25 respectively in Figs. 16 and 17.

In Fig. 13 a brass or phosphor bronze spring is shown. This spring is made substantially in the shape illustrated with a hole 33 in one end and a rounded portion 35 containing a slot 34, the purpose of which will presently appear. In Fig. 14 a standard type binding post member 36 is shown with a projecting portion 39 formed therein. In Fig. 15 the brass lock-ring 40 has a hole 41 formed therein to fit the upper portion of the shaft 17 or the lower shaft portion of member 17, and also contains another hole 42 of the same size as the hole 6 of member 1 which is shown in Fig. 6. The purpose of this ring will be presently described.

In Fig. 16, an insulating disk 43, preferably made from phenol condensation product, hard rubber, or other moulded insulating material contains the metal inserts 46, 50 and 51. These metal inserts are either cast in to said disk 43 or force-fitted therein. The member 43 also has imbedded or force-fitted into it a metal insert 44 which comprises a bearing 45 to fit the top portion of shaft 17 shown in Fig. 9. In Fig. 17 the lower insulating disk member 57 contains a similar inserted bearing 58 with hole 59 of size to fit the lower portion 17^a of shaft 17.

Fig. 18 shows the brass lock bar which is used to hold the member 1 to the shaft member 17.

Referring now to Fig. 1 and Fig. 2, the movable plates 1 are all of identical construction and are assembled on the shaft member 17 as follows:—The member 1 is inserted into its co-operating slot 24 of member 17, then lock bar 66 is slid through slot 26 of member 17 and through hole 6 of member 1 as shown. Next the two lock rings 40 are placed at each end portion of

member 17 as shown in such a manner that the hole 42 of lock ring 40 tightly holds lock bar 66. This securely locks each plate member 1 to shaft member 17. Also the counter-weight member 67 is similarly mounted on 70 and locked to shaft member 17 as shown. The purpose of the counterweight member 67 is to offset the weight of the movable plates 1, so that shaft 17 when set in a particular position will stay there. The illustration clearly shows it assembled so that anyone skilled in the art may make and use same. The stationary plates are assembled by merely inserting the plate member 7 into the co-operating slots 16 provided under 80 support member 15.

Now when the top insulating disk 43 and the bottom insulating disk 57 are joined as shown by support members 15 and support member 27, the stationary plate members 7 85 are held accurately and parallel with respect to said support disks 43 and 57 respectively. The machine screws 68 and 69 must be tightly fastened as shown. The shaft 17 also carries an insulating knob 70 with scale 90 or pointer 71 and lock screw 72 in its portion 73 whereby the shaft 17 may be easily rotated. The shaft 17 may thereby be rotated the full 360 degrees, and in no case will the rotatable plates 1, etc. ever touch 95 the fixed plates 7, 7, etc., owing to this new construction. The spring member 32 is mounted as shown to keep the shaft portion 18 of member 17 abutted against the top lock washer 40 which bears on metal insert 100 44 carried in insulating disk 43. A screw 74 permits the friction of the bearing of said spring member 32 against lower lock washer 40 to be adjusted. Spring member 32 also serves as a connection between binding post 36 and the movable plates' shaft 105 17. The other connection to the fixed plates is made by screw member 69. The counter-weight 67 is preferably shaped as shown in Figs. 2 and 3 so that its center of gravity 110 is of equal value to the center of gravity of all of the mounted movable plate members 1, etc. In case a condenser of smaller capacity is desired, it is merely necessary to remove a portion or a certain number of the plate members 1, etc. from the shaft 17, and to replace the remaining plate members 1 to afford a condenser of smaller capacity. In Fig. 4 the manner in which the plates are held is shown in detail. In Fig. 120 115

5 a further fragmentary view is shown in order to still more clearly show this assembly. It will be observed that in course of construction no solder is necessary in accordance with this invention.

My condenser may be used for a variety of purposes such as laboratory measurements, radio apparatus, transmitting and receiving sets and other electrical circuits. Insert members 46, 51 and 50 carry threaded 125 130

portions 47 so that the entire condenser may be mounted on any panel as is customary in the radio art without having any electrical connection between the mounting screws inserted into the thread 47 and the remaining metal portions of the condenser.

Having now clearly described and illustrated my invention, I will more particularly point out what is new and useful in the 10 appended claims. Various changes may be made within the spirit of this invention and within the scope of said appended claims.

I claim and these Letters Patent are to 15 be understood as set forth:—

1. A variable condenser comprising in combination, a rotatable shaft having a series of slots, rotor plates constructed to fit into said slots, a counter weight for said 20 rotor plates, a locking pin to fasten said plates and counterweight to said shaft, a pair of insulated bearing supports for said shaft, a series of stator plates carried in cooperative relation to said shaft bearing 25 supports, an adjustable friction member to hold said shaft and rotor plates spaced from said stator plates, and means to hold the rotor and stator plates in parallel alignment, including cooperating supports for said stator plates comprising slotted holders therefor.

2. In an air condenser for radio and other electrical circuits, a shaft, a series of plates mounted on said shaft, a lock-bar extending along one surface of said shaft and through said plates, a lock-ring co-operat-

ing with said shaft and said lock-bar, means to mount and support said shaft and a series of stationary plates supported by said last named support means.

3. In a radio condenser, in combination, a series of stationary plates, supporting means for said plates comprising three metal posts containing a series of slots of size such that said stationary plates may 45 be force-fitted into said slots, top and bottom members for said supporting mountings, a metal bearing comprised in each of said top and bottom mounting support members respectively, a shaft journalled in said 50 bearings, a series of slots carried and formed into said shaft, a series of plates carried by said shaft, and of such thickness as to fit snugly into said slots formed into said shaft, a locking member to secure each 55 of said movable plates to said shaft, and a co-operating slot longitudinally cut into said shaft to hold said lock bar.

4. In a radio condenser having rotor and stator plates the improvement which comprises a rotor member including a shaft and a series of rotor plates, the supporting surface between said shaft and plates being non-circular in contour, and a metallic element longitudinally disposed to bind said 65 rotor plates as a unit with said rotor member.

In witness whereof, I have hereunto subscribed my name and legal seal this 27th day of May, 1922, at New York city, county 70 and State of New York.

PHILIP E. EDELMAN. [L.S.]
